HAIR CURLER

Henry Paul Richard Sommers,
Wellesley Hills, Mass.

Application June 21, 1949, Serial No. 100,460

4 Claims. (Cl. 132—33)

1

This invention relates to hair curlers and has for its general object the provision of a novel and improved implement for curling the hair and for applying and securing pin curls in women's hair, in the preparation of a modern coiffure.

The present invention relates to the same general class of hair curlers as the one covered in my United States Patent No. 2,321,433, granted June 8, 1943, and reference is made to the specification of that patent for a full and complete discussion of the nature and functions of these implements, and descriptions of those features of construction which are common to the two inventions.

In its preferred embodiment, the present invention contemplates the provision of a rod-like combined curler and comb, although the comb obviously may be omitted without affecting the curler device located at the opposite end of the implement. The curler proper comprises a generally cylindrical rod made of wood, metal, or plastic and is preferably of polygonal, ribbed, or scalloped cross-section. The rod is hollowed out for some distance from the end and the annular walls thus provided are kerfed longitudinally to provide a pair of parallel slots upon either side of the cylindrical bore, within which a strand or hank of hair may be inserted before winding the curl.

In order to securely anchor the hair during the winding of the curl, and also to receive the curl retaining or locking means when one is used, there is provided a multi-toothed comb-like insert, socketed in the hollow end of the curler rod with its teeth or blades disposed edgewise of the parallel slots in the wall of the curler. The spaces between the blades or teeth of the retaining member are preferably quite narrow and the blades are preferably resilient; and the hair and the lock pin are effectively frictionally retained by the member until the curl is wound and removed from the curler.

Other objects of the invention and features of novelty will be apparent from the following specification when read in connection with the accompanying drawings in which one embodiment of the invention is illustrated by way of example.

In the drawings,

Figure 1 is a top plan view of a hair curler embodying the principles of the invention;

Figure 2 is a view in side elevation of the curler;

2

Figure 3 is a fragmentary longitudinal sectional view of the curler;

Figure 4 is a transverse sectional view taken on line 4—4 of Figure 3;

5 Figure 5 is a side view of the novel comb-like friction retaining element forming an important part of the curler;

Figure 6 is a transverse sectional view taken on line 6—6 of Figure 5;

10 Figures 7 and 8 are views showing two stages in the operation of the hair curler in curling a strand or tress of hair;

Figure 9 is an end view of the curler shown in Figure 7;

15 Figures 10 and 11 are fragmentary views of the same curler showing two stages in the operation of the device in making a pin curl;

Figure 12 is an end view of Figure 10 taken at the level of the strand of hair; and

20 Figure 13 is a transverse sectional view through the operative end of another embodiment of the invention;

Figure 14 is a view similar to Figure 13 but taken at a point adjacent the folded head portion of the lock hair pin.

In the exemplary embodiment of the invention which is illustrated in the drawings, the novel combination implement is designated generally by the reference numeral 10, and is seen to comprise the comb portion 11 and the curler proper 12, these instrumentalities being formed at opposite ends of the implement for ready accessibility and use in dressing and curling the hair.

The novel hair curler 12 with which the present invention is chiefly concerned comprises an approximately cylindrical portion of the instrument of somewhat larger diameter than the intermediate shank or handle portion 13. The outer surface of the curler 12 is preferably provided with a plurality of ridges or ribs 15, or it may be provided with grooves or given a polygonal cross-section, if desired, to facilitate removal of the curl.

The curler end 12 of the rod-like implement 10 is provided with a cylindrical recess 16 and the resulting annular walls of the curler are kerfed longitudinally as at 17 for the entire depth of the cylindrical opening, the kerfs being gradually widened as at 18 to provide a diverging entrance.

45 50 At the inner end of the cylindrical recess 16

there is provided an extension in the form of a socket 19 preferably of rectangular cross section. Into this socket there is secured the rectangular shank or butt portion 21 of a toothed or bladed comb-like member 20. The end 21 may be inserted in the socket 19 with a force fit or it may be cemented therein with a suitable adhesive.

The member 20 may be made of metal, wood, bamboo, plastic, or any other suitable material and is provided with a number of flat thin blades or teeth 22 which are resilient and disposed fairly closely together. These teeth 22 are approximately coterminous with the slots 17, are disposed edgewise thereto, and may be somewhat pointed at their outer ends as indicated at 23 in Figure 10.

One method of utilization of the improved curler is illustrated in Figures 7 and 8 of the drawings. A portion of the end of a hank of hair to be curled is impaled on the points of the multi-toothed comb-like retainer member 20 and is pushed into the slots or kerfs 17 of the curler 12. The hank or strand of hair is divided by the elongated teeth of the comb, a few hairs entering the narrow spaces between each pair of teeth and frictionally held there, as indicated in Figure 9.

The curler rod is then rotated and the curl 26 is wound thereon as clearly shown in Figure 8, whereupon it may be pulled off of the curler and set in place in the usual way by means of pins.

In Figures 10, 11 and 12, there is illustrated a mode of making and securing a curl in which a lock hair pin is employed, such a pin itself being a feature of the invention covered by my prior United States Patent No. 2,321,433. The lock pin 30 comprises a doubled piece of flexible paper, cardboard, fiber, thin metal, or plastic, having a somewhat T-shaped or Y-shaped configuration, the shank portion 31 being inserted lengthwise into the open end of the curler 12, the doubled thickness being received between certain of the central blades or teeth 22 of the retaining member 20, and the wider creased or folded cross portion 32 of the pin projecting laterally through the slots 17 as clearly shown in Figure 10.

The hank or strand of hair 25 is passed into the slots and between the teeth of the comb member 20 also, just as in the method illustrated in Figures 7 to 9, and the curl 26 is wound on the curler element 12 above the projecting ends of the head 32 of the lock pin 30. When the curl 26 is slid off of the curler it strikes these projecting ends and pulls the pin 30 out of the curler recess and the curl is safely held upon the pin. Then the doubled shank portions 31 may be separated, spread apart upon the opposite side of the curl from the creased head or cross portion 32, and secured in such spread position by means of a straight pin or wire threaded through the holes 33 in the same manner as fully described in my above-mentioned patent No. 2,321,433.

In Figure 13, there is illustrated a hair curler having a tubular curling portion 33 with somewhat thicker walls than the first described embodiment. A toothed element similar to the one shown at 20 in the first described embodiment is shown at 35. In this form there are provided angular, non-radial slots or kerfs 34. These slots open outwardly at the end of the implement just as in the case of the similar slots in the first described curler and are adapted to receive a strand of hair. The slots 34 are chordal with respect to the circular cross section of the curler body 33 but occupy parallel planes, and provide a zig-zag

bend in the hair and thus serve to frictionally retain the hair during the winding operation. If desired, the comb-like friction element may be omitted, the zig-zag configuration of the slots 34 serving to frictionally retain the hank of hair.

In Figure 14, there is illustrated a curler exactly like the one shown in Figure 13 but utilized as the one depicted in Figures 10, 11, and 12, the lock hair pin 30 being employed. In this case, the wing-like folded head 32 of the hair pin is forced to assume an S-shaped configuration in the zig-zag slots 34 and this increases the frictional holding of the pin as well as of the strand of hair. Otherwise, the construction and operation is the same as that described in connection with Figures 10-12.

Various changes and modifications may be made in the embodiment illustrated and described herein without departing from the scope of the invention as defined in the following claims.

What I claim is:

1. A hair curling implement comprising an elongated rod about which a strand of hair may be wound to form a curl, said rod having a socket in one end thereof; and a comb-like retainer member for frictionally receiving a portion of the strand of hair during winding of the curl, said member comprising a solid butt end rigidly received in said socket and a plurality of parallel, elongated, closely spaced, flat reed-like blades having free outer ends between which portions of the strand of hair may be resiliently clamped.

2. A hair curling implement comprising an elongated rod about which a strand of hair may be wound to form a curl, said rod being hollow for a considerable distance inwardly from one end thereof, comb-like retaining means for a hank of hair to be curled, said retaining means comprising at least three resilient, parallel, closely-spaced teeth secured together and fixed within the hollow interior of said rod at their inner ends, and having their outer ends free of contact with each other and with the rod, and openings in the walls of said hollow rod for entrance of the hair to be clamped between the teeth of said retaining means the several teeth serving to divide the hank of hair into a plurality of separately gripped sections.

3. A hair curling implement comprising an elongated rod-like member having a tubular end portion, the annular walls of said tubular end portion being kerfed from their outer ends inwardly thereon upon diametrically opposite sides of the member to provide transversely registering longitudinal slots through which the strand of hair to be curled may be passed, frictional comb-like hair retaining means secured within the hollow interior of said tubular end portion of the member and comprising a shank portion, a socket in the end wall of the hollow interior of the member for receiving said shank portion and at least three parallel, closely spaced elongated blades having free outer ends extending from said shank portion to the open end of said tubular portion of the member, the plural spacing between the blades being in transverse alignment with the slots in the walls of said member, whereby the hair may be introduced through the slots and a plurality of separate sections thereof frictionally retained between the several blades.

4. A hair curling implement of the class described comprising an elongated rod-like implement having a substantially cylindrical operative end portion, said end portion being of rigid and

non-articulated construction and made hollow to provide a single fixed relatively thick annular wall, a pair of longitudinally extending diametrically opposed slots in said wall extending from the end of said member to a point spaced inwardly therefrom, said slots being smooth-walled and planar but lying in different but parallel transverse planes, whereby the slots and the hollow interior of the implement provide a zig-zag frictional hair retaining passageway in the curler and a retaining member disposed within the hollow interior of said implement for also receiving the hair.
